UNITED STATES PATENT OFFICE.

JOSEPH ICHISHIMA, OF NEW YORK, N. Y.

LINK-CUFF HOLDER.

SPECIFICATION forming part of Letters Patent No. 578,456, dated March 9, 1897.

Application filed September 25, 1896. Serial No. 606,954. (No model.)

To all whom it may concern:

Be it known that I, JOSEPH ICHISHIMA, a citizen of the United States, and a resident of the city, county, and State of New York, 5 have invented certain new and useful Improvements in Link-Cuff Holders, of which the following is a full, clear, and exact description.

My invention relates to cuff-holders; and 10 it is designed, however, with special reference to the needs of that class of cuffs known to the trade as "link-cuffs"—that is to say, cuffs having the sides or ends secured together by means of buttons attached to either 15 end of a link.

The object of my invention is to furnish a cuff-holder for link-cuffs which is cheaply 20 manufactured and light and ornamental in appearance, and yet durable. It permits the use of both ends of the cuff; it prevents injury to the sleeve-lining of the coat; it is concealed from view when in place in the cuff; it furnishes a firm and secure fastening for 25 the cuff to the shirt-sleeve, and automatically adjusts itself to any angle to which the cuff may be pressed or bent.

The nature of my invention and the manner in which the same is or may be carried into effect can best be explained and understood by reference to the accompanying drawings, in which—

Figure 1 is a perspective view of a link-cuff holder made in accordance with my invention. Fig. 2 is a transverse section. Fig. 3 is a top plan view of the holder, and Fig. 35 4 is an edge or side view of the same.

In the accompanying drawings, A represents the cuff-holder proper, one end of which is provided with a button or stud B, whose 40 head is either jointed or solid with the stem, as may be desired. The other end is provided with a hole C or other suitable loop for fitting around the stud or button of the band on the shirt-sleeve to secure the cuff in proper adjusted position. The holder proper is jointed 45

at or near its center, and for this purpose is preferably provided with a hinge D, which, when the holder is in use and placed in position, will automatically adjust itself to any style in which the cuff is worn, either flat or 50 round style.

In using my improved device, subject matter of my application, the end having the hole C in it is passed over the button or stud on the band of the shirt-sleeve. One of the 55 lower ends of the link-cuff is then buttoned onto this same stud in the shirt-sleeve band. The other end of the cuff is now buttoned onto that end of the device having the jointed or solid button B, whereby both ends of the 60 cuff are firmly and evenly secured upon the band of the shirt-sleeve.

It will be noticed that a cuff-holder thus formed is beneath the cuff and wholly concealed from view; holds the sides or ends of 65 the cuff closely together, (allowing no flaring or gaping apart of the ends;) prevents the wearing out or injuring of the lining of the coat-sleeve; does not injure the shirt-sleeve, and adjusts with a marked degree of nicety 70 the cuff throughout its length, so as to make the size of the cuff the same at both ends; and, furthermore, the device being flexible at its center it will automatically adjust itself to any position necessary, whether the cuff 75 be worn in a flattened style, as is now very usual, or in a rounded fashion.

Having described my invention, what I claim is—

A cuff-holder having a button or stud at 80 one end and a hole or loop at the other end, the parts carrying the said loop and button being jointed together, substantially as and for the purposes hereinbefore set forth.

In testimony whereof I have hereunto set 85 my hand this 23d day of September, 1896.

JOSEPH ICHISHIMA.
